FOLDABLE SERVING TABLE

Filed May 21, 1946

UNITED STATES PATENT OFFICE

2,593,471

FOLDABLE SERVING TABLE

Bruno Mayer, New York, N. Y.

Application May 21, 1946, Serial No. 671,372

6 Claims. (Cl. 311—85)

1

This invention relates to foldable serving wagons or tables wherein the top of the wagon or table may be used as a manually-transported tray when desired, the supporting legs therefor being foldable to extend below or to underlie the tray when it is being so carried.

It has heretofore been proposed to construct foldable serving devices or conveyances adapted for conversion into serving trays. To this end, the legs of such devices were arranged to be manipulated to cause them to be swung against the underside of the device or table.

It is also known to have said legs hinged and spring-actuated and to release said legs to thereby move the same from one position to another position.

These known constructions, however, did not comply with the practical requirements which often necessitated that the legs of the device or table had to be lengthened or shortened to adjust the height of the table relatively to chairs or to other pieces of furniture.

The present invention overcomes these and other disadvantages and has as one of its objects the provision of means facilitating the extension of the legs of the wagon or table from above the top thereof.

Another object of the invention is to provide means permitting the operation of a mechanism for causing extension of the legs, as well as for swinging the legs when the same are retracted, to a position underneath the top of the table which forms a tray or the like.

A further object of this invention is to provide means for rotating or moving an accessory implement associated with the tray relatively to said tray when the wagon or table is in operative position and preventing movement or displacement of said implement when said wagon is in inoperative position or is converted into a serving tray.

Still another object of the invention is to provide a serving table with foldable legs and means for holding said legs in either folded or extended position, the latter means including a lock which is controlled by a manually movable sliding element.

Yet, a further object of the invention resides in the provision of extensible legs composed of telescopic elements, and locking means for holding said elements in any adjusted relation, said locking means being suitably coupled to and controlled by movement of the sliding element, whereby movement of said sliding element will free the locking means for the sections of the legs, as well as free the lock which holds the legs

2

in table-supporting position, the movement of said sliding element first permitting telescopic movement of the leg sections to shortened position and then permitting the legs in such shortened position to be swung flatwise against the underside of the tray portion of the table or wagon.

With the above and other objects in view which will appear as the description proceeds, the invention resides in the novel construction, combination and arrangement of parts substantially as hereinafter described, and more particularly defined by the appended claims, it being understood that such changes in the precise embodiment of the herein disclosed invention may be made as come within the scope of the claims.

In the accompanying drawing which discloses a preferred embodiment of the invention,

Fig. 1 is a view looking at the underside of the table with the legs thereof in folded position;

Fig. 2 is a sectional view of Fig. 1, taken on line 2—2 and looking in the direction of the arrows;

Fig. 3 is a sectional view through one end of the table showing one pair of legs in the act of being folded;

Fig. 4 is a sectional view taken along line 4—4 of Fig. 2 and looking in the direction of the arrows;

Fig. 5 is a detail view of one of the operating slides located at the ends of the table, by means of which folding of the legs is facilitated;

Fig. 6 is a view of a similar slide having a modified form of aperture by means of which the release of the locking means for the telescopic elements of the legs is secured;

Fig. 7 is a sectional view along line 7—7 of Fig. 6 and looking in the direction of the arrows;

Fig. 8 is a view similar to that of Fig. 7, disclosing a modified form of release mechanism.

With reference to the drawing, there is shown in Fig. 1 the top of the table 10 which, under certain conditions, and while the legs of the table are in folded position, will act as a serving tray. A circumferential wall 11 extends around the sides of top 10 which wall has a downwardly extending skirt portion 12 forming an enclosure into which the legs may be folded and substantially concealed from view, as will be hereinafter described.

At a substantially central position, top 10 of the table on which any objects, such as glasses (not shown), may be placed, is provided with a rotatable implement or turntable 13 which may be suitably partitioned as shown at 14, if so desired, 55 to divide it into compartments for holding various

articles, such as bottles of beverages, food or the like. The turntable 13 carries a central axle 15 which rotates in top 10 of the table or in a suitable bearing provided therein so that the aforesaid articles may be moved relatively to the remainder of top 10 and objects placed on the latter. Secured on axle 15 below the bottom of top 10 is a spider 16 having several radially-extending arms 17 adapted to be engaged by the legs of the table when the legs are in folded position, as shown in Fig. 1, at which time the table is being used as a serving tray and carried around by a person while the turntable or rotary tray 13 is prevented from rotative movement.

The table is provided with two pairs of legs 18, 19, respectively. The pair of legs 19 is spaced wider apart than the pair of legs 18 so that the latter pair, when folded, will lie between the pair 19, as it is clearly seen in Fig. 1. The construction of each pair of legs and its attachment to the table is similar and therefore the description of one pair of legs, say, 19, will suffice for both.

The pair of legs 19 is connected at the top by the cross piece 20, which is hinged at 21 to a transversely extending reinforcing piece 22 secured to the underside of the table top 10. Each leg of the pair of legs 19 is composed of a pair of tubular telescoping elements or sections, the fixed or upper section of each leg being shown at 23. The upper end of each of the fixed leg sections 23 is secured in the cross piece 20 by means of the straps 24 which, in turn, are attached to the leg section 23 and to the cross piece 20 by means of screws 25a or similar fastening means. Through this arrangement, fixed leg sections 23 are securely affixed to cross piece 20 and project therefrom, as clearly shown in the drawing.

The movable or adjustable section of each leg is indicated at 25, the same being adapted to telescope into or out of the fixed leg section 23 to a selected extent and to be maintained in any predetermined position of projected adjustment, as will be hereinafter described.

The slideable or movable leg section 25 is formed with a plurality of spaced holes or apertures 26, any one of which is adapted to be selectively engaged by a pin 27, projecting laterally from the end of a lengthy lever 28 which extends downwardly through the telescoped leg sections or elements 23 and 25. Pin 27 projects through a hole 26 in the movable leg section and when further extended through hole 29 aligned with, say, 26a, it will be clear that the movable leg section can be held in its retracted position.

Each of the levers 28 is pivoted in a bracket 30 located within the upper portion of the fixed leg section 23. The upper end of the lever 28 for one of the legs 19 beyond the pivot is secured to one end of a link or adjustable cable 31 extending through a passage 32 into the cross piece 20 and having its opposite end secured to one end of a lever 33. The companion leg 19 has its lever 28 attached to a link 31a, the end of which is attached at 34 to the second end of lever 33. Lever 33 is attached to a pin 35 which is pivotally mounted in the cross piece 20. Also attached to pin 35 is one end of a bell-crank shaped lever 36 having its opposite end provided with a laterally extending pin 37 which enters an inclined slot 38 formed in a slot 39 which is mounted to slide through a slot 40 formed in the angularly bent end 45 of a shield or guide

plate 46. This plate 46 is attached by the screws 47 to an end face of the cross piece 20.

The arrangement is such that when the bell-crank lever 36 is moved in the proper direction, it will pivot the lever 33 about pin 35, causing the same to exert a pull on the two links or cables 31 and 31a with the result that levers 28 will be swung on their pivots to cause them to draw their pins 27 out of the holes 26a and 29 to permit extension of the movable leg sections 25 with respect to the fixed leg sections 23 in which they are disposed.

Near the points of connection of levers 28 to links 31 and 31a are provided springs 48 which normally tend to hold levers 28 in a position wherein pins 27 thereon are in engagement with respective holes 26.

A stop pin 49 is located within each of springs 48, the same serving to limit movement of the levers 28 toward release position and thereby preventing jamming or sticking of the levers within the hollow leg sections.

The means for maintaining the legs in either extended table-supporting or folded positions consists of a hinge-like member 50 having a guide leaf 51 formed with a forward end 52 normally locking or abutting against the front of lower portion 53 of plate 46. Lower portion 53 of this plate projects slightly below the cross piece 20 to be thereby readily engageable with the end portion of leaf 51. The engagement of the lower end portion 53 of plate 46 with and along leaf 51 occurs when the legs are to be swung underneath the table or tray. Slide 39 is provided at the top with a cylindrical handle portion 54 which may be readily engaged by the fingers of a person to depress slide 39 and when this is done an angular foot portion 55 on the lower end of the slide will engage leaf 51 and depress it (Fig. 3) against the pull of a spring 56 which connects leaf 51 to the end of a companion leaf 57 secured to a cross member 58 on the bottom of the tray.

When leaf 51 is depressed it will be observed that the end 52 of the leaf is shifted for engagement with and below the lower end 53 of plate 46 and thus, when the two slides 39 controlling the two pairs of legs 18 and 19, are downwardly depressed, the legs will be free to be manually swung inwardly to folded position and to overlie the bottom surface of table top 10.

When the legs are disposed in said folded position, it will be seen that the same bear against arms 17 of spider 16 and act to prevent rotative movement of the turntable or rotary tray 13. Thus, while the table is being used as a serving tray, and is being carried by handles 59 located at the opposite end of the tray or table, and with the legs of the table in folded position, the turntable 13 will be prevented from rotative movement.

When the legs are folded they will be held in such position by pressure of leaves 51 against the outer face of each of the plates 46, as noted in Fig. 1. To open the legs, plates 39 are swung by means of handles 54 in the direction of arrow A, this serving to swing the legs to table supporting position and bringing the ends of leaves 51 into locking engagement with the plate ends 53 (Fig. 2) to hold the legs in such table supporting position.

The angular disposition of each of the slots 38 in slides 39 is such that when slides 39 are depressed, pins 37 will be shifted arcuately as shown by the dot-dash line in Fig. 5, this movement

5

tending to swing the bell-crank 36 and cause pivotal movement of lever 33 which results in freeing pins 27 from holes 26a and 29 in the leg sections. The result is that when slides 39 are depressed, the depressing movement of these slides will also serve to free the movable leg sections 25 so that they may be telescoped within the fixed leg sections 23 while the legs are swung to supporting position.

With the angular arrangement of slots 38 (Fig. 5), it will be noted that when the legs have been extended to table supporting position and if it will then be necessary to swing the legs to folding position, pressure must be exerted on bell-crank levers 36 to free pins 27 and permit upward telescopic sliding movement of movable leg elements 25 within their outer sections 23 to thereby secure the retracted position (shown in full lines in Fig. 4).

In other words, with this arrangement the adjustment of the length of the legs must be achieved by operation of the bell-cranks 36 after the legs have been unfolded. With an arrangement as shown in Figs. 6 and 7, the freeing of pins 27 from holes 26a and 29 can also be secured independently of the swinging of the legs to open position. It will be noted that in this embodiment pin 37 is operative in a substantially triangular slot 60 in slide 39, and that said pin is provided with a finger piece 61. When it is desired to swing the legs to extended or table supporting position, and at the same time free the telescopic elements of the legs, finger pieces 61 may be engaged to swing the bell-crank levers and cause freeing of pins 27.

At the same time as the legs swing to open position, the movable leg elements 25 will slide to extending positions according to the desired height of the table. By holding the table with its top at the desired height from the floor and then releasing pressure on pins 37, pins 27 will find their way into the required holes 26 to support the table at that desired height.

Movable leg elements 25 are held against rotation within the fixed leg sections 23 by means of a groove 62 provided in the movable leg elements and which is engaged by a guide screw 63 disposed at the fixed leg sections. The upper end of this groove is closed to limit outward sliding movement of the movable leg elements and prevents separation of the same from the fixed sections within which they are slid able. Casters 64 or other suitable wheels may be provided at the ends of the movable leg elements and each pair of legs may be connected by the cross brace 65.

From the foregoing, the operation of the device will be clearly understood. In Fig. 4 it is shown, that the legs for use in connection with a serving table are in open or supporting position. Should it be desired at any time while the legs are in said supporting position, to increase or decrease the length of the legs, this may be done by pressing both slides 39 slightly downwardly (Fig. 5) during a predetermined length of stroke or by actuation of handles 61 (Figs. 6 and 7) until pins 27 are freed from the holes 26a, 29 (Fig. 4) and the table may then be raised to allow the movable leg elements to drop and extend (or again to retract, as the case may be) as shown in dot-dash lines in Fig. 4.

When it is desired to use the device as a tray, slides 39 are depressed by means of handles 54, thus first permitting the leg extensions to be telescoped and retracted (until pins 27 again

6

register with and engage holes 26a, 29 of Fig. 4), and then as further depression of slides 39 forces leaves 51 to engage with the lower ends of plates 46 (Fig. 3), the legs can be swung toward each other to folded position (Fig. 1).

This will dispose the legs in position where they will be concealed by the skirt portion 12 of the table end, when folded, the legs will engage against arms 17 of spider 16 and impede thereby the movement of turntable 13.

Fig. 8 illustrates a fragmentary sectional view of a modified form as it is applicable to the release mechanism. Hand lever 70 is guided by means of a bolt 71 within opening 73 of the slide 39. Lever 70 is pivoted at 74 on a lug or similar bearing of slide 39. When lever 70 is actuated in the direction of arrow C against the action of coil spring 72 which is seated on bolt 71, the lever end 75 will engage pin 37 and cause downward movement of said pin 37 to thereby actuate lever 36 for the release of the pins 27. Thus, adjustment of the height of the table legs may be had independently of slide 39. Slide 39 may, however, also be employed (by pressing the same at 54 in the direction of arrow B) to cause on the one hand actuation of the pins 27 which, as hereinabove explained, are operatively connected through levers 36 and pins 37 to slide 39, and on the other hand actuation of the leaves 51 for the purpose of first retracting and then folding the legs 18-19 below the table top.

It will thus be seen that there has been provided by this invention a device of the character described in which the various objects hereinabove set forth, together with many thoroughly practical advantages, are successfully achieved.

As many possible embodiments may be made of the above invention, and as many changes might be made in the embodiment above set forth, it is to be understood that all matters hereinbefore set forth or shown in the accompanying drawing, are to be interpreted as illustrative and not in a limiting sense.

Having thus described the invention, what is claimed as new and desired to be secured by Letters Patent is:

1. In a table structure of the character described; a table top having two pairs of legs hingedly attached at its underface, each pair of legs being attached, respectively, to a cross-piece, spring supported means disposed at a respective cross-piece and including slidable means, each leg including at least two sections, said sections being adjustable to each other to change the effective length of said legs, locking means engageable with said leg sections in adjusted relation of the latter, and means coupling said leg locking means with said slidable means of said spring supported means whereby movement of said slidable means against said spring supported means will permit swinging movement of said legs and cause release of said leg locking means.

2. In a table structure, a table top having handles by which it can be carried and used as a tray, legs swingably attached to said table top, said legs including each a section telescopically extensible in relation to each of the remainder of said legs so as to regulate the effective length of said legs, said sections of said legs having predetermined holes, locking means disposed within said legs for selective engagement with said holes in said sections to hold said sections in fixed relation, slidable means actuatable to facilitate swinging movement of said legs relatively to said table top, said slidable means being oper-

atively connected with said locking means for engaging said holes in said legs whereby said sections of said legs will be released for movement upon operation of said slideable means.

3. A table of the character described comprising a table plate having an upper surface for supporting articles thereon and an underface, pairs of legs disposed at opposed ends of said underface, respective leg extensions engaging said pairs of legs to change the length of the latter, a cross piece interconnecting each pair of legs, hinge means swingably connecting said cross pieces to said table underface, a mechanism positioned at each of said opposed ends for actuating said pairs of legs, respectively, so that said pairs of legs assume, respectively, table-supporting position and folded position in which latter position said legs extend below said table plate in substantially lengthwise direction of said underface, each mechanism comprising a slide, a guide plate fixed to the respective cross piece and provided with a slot for guiding said slide into a predetermined position, spring means arranged at the underface of said table plate and including a leaf member engaging under the action of said spring means said guide plate so as to lock each pair of legs in said table-supporting position, lever means operatively connected to said leg extensions for releasing the latter for adjustment relatively to said pairs of legs, and means positioned adjacent said slide and adapted to actuate said operatively connected means, said slide being adapted in said predetermined position to bring about disengagement of said leaf member from said guide plate to free the latter and to permit said pair of legs to swing to said folded position below said underface of said table plate.

4. A table of the character described comprising a table plate having an upper surface for supporting articles thereon and an underface, pairs of legs disposed at opposed ends of said underface, respective leg extensions engaging said pairs of legs to facilitate adjustment of length of the latter, a cross piece interconnecting each pair of legs, respective hinge means swingably attaching said cross pieces to said table plate at its underface, a mechanism positioned at each of said opposed ends for actuating said pairs of legs, respectively, so that said pairs of legs assume, respectively, table-supporting position and folded position in which latter position said legs extend below said table plate in substantially lengthwise direction of said undersurface, each mechanism comprising a slide, a guide plate fixed to the respective cross piece and provided with a slot for guiding said slide into a predetermined position,

spring means arranged at the underface of said table plate and including a leaf member engaging said guide plate so as to lock each pair of legs in said table-supporting position, lever means operatively connected to said leg extensions whereby the latter may be released for adjustment relatively to said pairs of legs, and means controlled by said slide and adapted to actuate said operatively connected means, said slide being adapted to said predetermined position to bring about disengagement of said leaf member from said guide plate to free the latter and to permit said pair of legs to swing to said folded position below said underface of said table plate.

5. In a table structure, a table top having legs swingably arranged thereon and foldable beneath it, said legs being provided with telescopic sections to extend said legs in lengthwise direction of said legs, means releasably holding said legs in either of two positions, respectively, and relatively to said table top, means for locking said telescopic sections of said legs in predetermined position lengthwise of said legs and slideable means arranged to operate said leg holding means and simultaneously said locking means, whereby said locking means will be freed upon release of said leg holding means to one of said two positions.

6. In a table structure according to claim 5, wherein a portion of said leg holding means normally extends at an angle to said slideable means, each of said leg locking means being provided with an element engageable with said leg sections, said element being operatively connected to said slideable means and caused to be moved relatively to said leg sections upon movement of said slideable means against said portion of said leg holding means.
